UNITED STATES PATENT OFFICE

2,457,470

INSULATED CHIMNEY

Ernest O. Howle, Chicago, Ill.

Application December 5, 1945, Serial No. 632,863

3 Claims. (Cl. 72—92)

1

The present invention relates to an insulated chimney and has to do with a chimney construction of such character that the chimney may be erected next to framework of buildings without any fear of fire hazard.

The present invention is useful in connection with the erection of housing projects wherein minimum cost and efficiency are necessary, although it is adaptable for use on any kind of building construction.

An object of the present invention is to provide an insulated metal chimney having means for maintaining the exterior of the chimney at temperatures below the ignition points of usual building materials.

The chimney construction of the present invention is shown as a sectional chimney, the sections comprising inner and outer metallic tubes with the space between them filled by finely ground heat insulating material.

The objects of the present invention will be apparent from the following description and accompanying drawing.

The accompanying drawing illustrates a chimney construction of the present invention and the views are as follows.

Fig. 1 is a vertical sectional view through a chimney;

Fig. 2 is an enlarged cross sectional view taken in the plane of line 2—2 of Fig. 1; and

Fig. 3 is an enlarged fragmental view of a joint between the sections of the chimney.

The drawing will now be explained.

The chimney shown in Fig. 1 includes a plurality of sections arranged one on top of another and comprising a lower section 5 and a plurality of upper similar sections 6.

The section 6 includes an inner liner of vitrified enameled metal having at its upper end a socket 7 to receive the lower end 8 of an adjacent upper section in nested relation. The inner liner is designated 9.

Spaced from the liner 9 is an outer casing member 10 to provide an annular space between the casings 9 and 10. This space is filled with powdered insulating material such as aluminum silicate, designated as 11, which I have found to be a very excellent heat insulator.

In order to prevent the powdered material from escaping between the spaces 9 and 10, plugs are inserted at each end of the section. The plugs 12 are annular members made of powdered aluminum silicate and a suitable binder so that when the plugs are inserted in place at the ends

2

of the sections, the powdered insulating material 11 is prevented from escaping.

Referring to Fig. 3, it will be noted that angle flanges 13 are secured to the lower ends of the inner casings 9 to extend into the space between the casings 9 and 10, and that the outer margins of the outer casings 10 are indented as at 14. The plugs 12 are held in place by the angle members 13 and the indentations 14.

5 The lowermost section 5 has a closed lower end and a lateral take-off 15 to which the pipe from a heater is connected.

The lower section 5 comprises an inner casing member 16 and an outer casing member, both 15 of which are formed to the particular shape desired, and the spaces between these sections are filled by insulating material 16 held in place by a plug 12 at the upper end of the section, and a similar plug 12 at the end of the take-off section 15.

20 Communicating with the lower end of the flue—that is, with the space within the inner casing 9, is a drain pipe 17 which may be connected to a sewer to draw off any condensation that may accumulate in the lower end of the chimney.

The chimney is erected by piling sections one on top of another to the desired height.

Tests of the chimney construction of the present invention have shown a maximum temperature on the outside of the casing 10 of 195° F., with a stack temperature of 1000° F.

25 The ignition point of certain building materials, as supplied by the National Fire Products Association, discloses the following:

	°F.
White pine	406
Long leaf pine	428
Cedar	370

30 The Bureau of Standards gives the ignition point of Yellow Pine as 496° F.

It will therefore be readily observed that the chimney construction of the present invention makes possible the erection of a sectional chimney of more than adequate protection against fire hazard, so that a chimney of the present invention may be erected in contact with frame building material.

35 In connection with the test above mentioned, it may be noted that the temperature in the heater was 1500° and the heater was placed 36 inches away from the chimney.

40 The invention has been described herein more or less precisely as to details, yet it is to be understood that the invention is not to be limited

thereby, as changes may be made in the arrangement and proportion of parts, and equivalents may be substituted without departing from the spirit and scope of the invention.

The invention is claimed as follows:

1. A sectionalized chimney comprising a plurality of sections, every section having a vitrified metallic flue casing and an outer metallic casing spaced from the flue, and a filling of finely ground aluminum silicate filling the space between the casings, and end plugs comprising rings of aluminum silicate and a binder for preventing escape of the powdered insulating material.

2. A sectionalized chimney comprising a plurality of sections, every section having a vitrified enamel coated metallic flue casing and an outer metallic casing spaced from the flue, and a filling of fine particles of insulating material such as aluminum silicate filling the space between the casings, and end plugs comprising rings of refractory material and a binder for preventing escape of the powdered insulating material.

3. A bottom section for a sectionalized chimney comprising an outer casing of generally cylindrical form with a closed bottom and a lateral flange, an inner section of the same general sec-

tional outline but of less dimension in diameter and length arranged within the outer section, said inner section having a lateral flange within and spaced from the lateral flange of the outer

5 casing, the space between said casings and the flanges being filled with fine particles of insulating material such as aluminum silicate with the material at the lower end of the closed bottom of the inner section between it and the lower bottom of the outer section, and ring plugs closing the space between the casings at the upper end thereof and the space about the ends of the flanges.
